DESCRIPTION

FIG. 1 is a perspective view of a speaker diaphragm dome showing my new design;

FIG. 2 is top plan view thereof;

FIG. 3 is a bottom plan view thereof;

FIG. 4 is a front elevational view thereof;

FIG. 5 is a rear elevational view thereof;

FIG. 6 is a left side elevational view thereof, the right side being identical; and,

FIG. 7 is a cross sectional view along the line 7—7 of FIG. 2.

The broken line showing on the drawing disclosure is for illustrative purposes only and forms no part of the claimed design.
